UNITED STATES PATENT OFFICE.

FRANK CANFIELD, OF DENVER, COLORADO, ASSIGNOR OF ONE-HALF TO PATRICK F. CARNEY, ONE-FOURTH TO GEORGE DODGE, AND ONE-FOURTH TO W. H. TOWNSEND, OF DENVER, COLORADO.

JAR-CLOSURE-FASTENING DEVICE.

SPECIFICATION forming part of Letters Patent No. 784,983, dated March 14, 1905.

Application filed June 15, 1904. Serial No. 212,716.

To all whom it may concern:

Be it known that I, FRANK CANFIELD, a citizen of the United States, residing in the city and county of Denver and State of Colorado, have invented certain new and useful Improvements in Jar-Closure-Fastening Devices; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in fastening devices for the caps or closures of jars or other receptacles where it is necessary or desirable that the caps shall be held tightly in place in such a manner as to form an airtight and liquid-tight joint.

My present object is to provide a device of this class which shall be extremely simple in construction, economical in cost, reliable, durable, and efficient in use; and to these ends the invention consists of the features hereinabove described and claimed, all of which will be fully understood by reference to the accompanying drawings, in which is illustrated an embodiment thereof.

In the drawings, Figure 1 is an elevation of a jar equipped with my improved device for fastening the cap in place. Fig. 2 is a sectional view taken through the jar and a locking-cam connected with the bail. Fig. 3 is a top view of the locking device shown in detail. Fig. 4 is a perspective view in detail of the locking-lever. Fig. 5 is a plan view of the blank from which the said lever is formed. Fig. 6 is a detail view of the bail, partly broken away on one side.

The same reference characters indicate the same parts in all the views.

Let A designate the body of the jar or other suitable receptacle to which a cap B is applied, a gasket C being interposed between the cap and the top of the jar, the said parts being of ordinary construction.

My improvement consists of a bail D, whose extremities are pivotally connected with the

jar by means of recesses which the extremities of the bail are bent to engage, as shown at D', the top of the bail being provided with a recess formed by an upward bend D'', and a lever E, which is provided with an opening E' through which the bail passes, one arm of the lever being adapted to engage the top of the jar, while the other arm is thrown down upon the bail, as shown in Figs. 1 and 3 of the drawings. The bend D'' in the bail allows the narrow part E'' of the lever adjacent the bail to enter when the lever is thrown to the locking position, thus preventing the lever from sliding in either direction upon the cap or closure of the receptacle. As shown in the drawings, this lever is stamped from a blank of the general construction shown in Fig. 5, whereby the arm E''' of the lever is exteriorly curved to straddle the bail when thrown down thereon, while the opposite arm of the lever is composed of two parts E'', one being located on each side of the bail. These parts E'' bear upon the top of the cap B when the lever is in the locking position or that shown in Figs. 1 and 3.

It is evident while my improved device may be stamped out of a piece of sheet metal that the same may be cast or otherwise formed as may be desired, since it is immaterial how it is made so long as the general construction is adhered to. Attention is therefore called to the fact that I do not limit myself in extreme details to the construction herein shown, as I am aware that it may be modified without departing from the spirit of the invention.

Attention is called to the fact that the narrow part E'' is recessed or bent downwardly slightly in order to receive the top of the bail, thus making a better fit when the locking device is in place than might otherwise be secured.

In applying the device the lever is first threaded onto the bail by passing one end of the bail through the opening E'. The bail is then applied to the jar or other receptacle. The lever is run upwardly on the bail until the central bend is reached. Then as soon as the closure or cap is applied to the jar or re-

ceptacle the bail is thrown downwardly to the locking position.

Having thus described my invention, what I claim is—

- 5 1. In a fastening device for the closures of receptacles, the combination of a bail whose extremities are pivotally connected with the body of the receptacle, and a lever provided with an opening through which the bail is 10 passed whereby the bail becomes a fulcrum for the lever, the opening through which the bail passes being intermediate the arms of the lever, one arm of the lever being adapted to engage the closure and the other arm the bail 15 when the lever is thrown to the locking position.
2. In a device of the class described, the combination with a receptacle and its closure, of a bail pivotally mounted on the body of the receptacle, a lever having an opening to receive the bail, an arm extending downwardly from the opening to engage the closure, and another arm extending beyond the opening and adapted to engage the bail when the lever is in the 25 locking position.
3. The combination with a receptacle and its cap or closure, of a bail whose extremities are pivotally connected with the receptacle and having an upward bend above the closure, 30 and a lever threaded on the bail and having one arm engaging the cap and the other arm engaging the bail when the lever is in the

locking position, the lever having a part which engages the bend in the bail from below when the device is locked.

35

4. The combination with a receptacle and its closure, of a bail whose extremities are pivotally connected with the body of the receptacle, the bail having a central upward bend, and a lever having an opening intermediate its extremities through which the bail passes, the said lever having a part located adjacent the opening and adapted to engage the bend of the bail when the lever is thrown to the locking position, one arm of the lever 40 projecting below the opening to engagement with the cap or closure, and the other arm projecting forwardly from the bend in the bail when the lever is in the locking position.

40

5. In a device of the class described, the combination with a receptacle and its closure, of a bail mounted on the body of the receptacle, and a locking-lever having an opening through which the bail passes, the bail serving to hold the lever in place, the lever extending lengthwise of the bail when in the locking position and having a groove in which the bail is received, substantially as described.

45

In testimony whereof I affix my signature in presence of two witnesses.

FRANK CANFIELD.
